US00D776411S

(12) **United States Design Patent** (10) Patent No.: **US D776,411 S**
Christensen et al. (45) Date of Patent: ** Jan. 17, 2017

(54) **SHOE**

(71) Applicant: **Reebok International Limited**, London (GB)

(72) Inventors: **Brian Christensen**, Centerville, MA (US); **Dennis Gaboriault**, Millbury, MA (US); **Ricardo Vestuti**, Providence, RI (US)

(73) Assignee: **Reebok International Limited**, London (GB)

(**) Term: **14 Years**

(21) Appl. No.: **29/498,683**

(22) Filed: **Aug. 6, 2014**

CLAIM

The ornamental design for a shoe, as shown and described.

DESCRIPTION

FIG. 1 is a front perspective view of a shoe showing the claimed design;

FIG. 2 is a right side view thereof;

FIG. 3 is a left side view thereof;

FIG. 4 is a top plan view thereof;

FIG. 5 is a bottom view thereof;

FIG. 6 is a front view thereof; and,

FIG. 7 is a rear view thereof.

The broken lines in the figures show portions of the shoe that form no part of the claimed design.

1 Claim, 6 Drawing Sheets
